CLAIM

The ornamental design for a jewelry bag, as shown and described.

DESCRIPTION

FIG. 1 is a side perspective view of the new design of a jewelry bag;

FIG. 2 is a front elevation view thereof;

FIG. 3 is a rear elevation view thereof;

FIG. 4 is a left side view thereof;

FIG. 5 is a right side view thereof;

FIG. 6 is a top view thereof;

FIG. 7 is a bottom view thereof;

FIG. 8 is a side perspective view thereof, illustrating that the jewelry bag is in a half-closed state; and,

FIG. 9 another side perspective view thereof, illustrating that the jewelry bag is in a closed state.

The broken lines show portions of the jewelry bag that form no part of the claimed design.
